UNITED STATES PATENT OFFICE.

FRANK M. TUBBS, OF SANTA ROSA, CALIFORNIA.

RAIL-SECURING DEVICE.

Application filed October 4, 1921. Serial No. 505,230.

To all whom it may concern:

Be it known that I, FRANK M. TUBBS, a citizen of the United States, residing at Santa Rosa, in the county of Sonoma and 5 State of California, have invented new and useful Improvements in Rail-Securing Devices, of which the following is a specification.

This invention relates to a rail securing 10 device, and the object is to provide means of particular construction for preventing the spreading of the rails.

A further object is to provide a plate 15 member or members upon which the rail is to be mounted and adjustable securing devices for engaging the flange of the rail from opposite sides thereof.

A still further object is to provide a plurality of plate members each carrying upwardly projecting elements, one of which elements constitutes a rail engaging device, said upwardly extending elements on the adjacent plates being in reverse relation, and oppositely located elements on a given side 25 of the rail being constructed for adjustable connection by means of bolts, permitting of the engagement of the rail flange from opposite sides thereof.

With the foregoing and other objects in view, the invention consists in the novel construction and arrangement of elements described and claimed, it being understood that modifications may be made within the scope of the claim without departing from 30 the spirit of the invention.

In the drawings, Figure 1 is a perspective view of the device, the rail being broken away; Figure 2 is a top plan view; Figure 3 is a perspective view of one of the two elements used in securing each rail to a given 40 tie.

The plate members 10 and 12 are each provided with slots such as at 13, for securing these plates to the tie by means of spikes.

Formed on one edge portion of the plate 45 10 is an upwardly extending element 14 provided with a slot 15 for receiving a bolt 17.

On the corresponding end of the plate 10 and on the edge immediately adjacent to the 50 inner edge of the plate 12 is an upwardly extending member 18 provided with a slot

registering with the slot 15 previously referred to, this slot in the element 18 receiving the bolt just mentioned, and the slots permitting of adjustment. The element 18 55 is cut-away at one lower corner providing an overhanging portion 20 and a slot similar to slot 29 mentioned below, these portions directly contacting with the flange 22 of the rail.

On the other end of the plate 12 and opposite the element 18 is an upwardly extending member 24 provided with a slot similar to slot 15, this member 24 corresponding with the element 14, but being on the opposite side of the rail when the parts are in operative position.

The plate member 10 is further provided with an upwardly projecting member 26, having a slot 27, and the portions 28 and 29 70 directly engaging the rail flange. A bolt 30 passes through the slot 27 and through element 18 and adjustably connects the elements 26 and 24 so that the portions directly engaging the rail flange may be brought into 75 intimate contact therewith.

It will be observed that the inner walls of the elements 14 and 24 are beveled, and when the devices are in position with one edge of the rail flange in approximate contact with 80 the lower part of the beveled portion, the other edge of the rail flange is engaged by the overhanging portions 20 or 28, as the case may be.

In placing the plates in position beneath 85 the rails, the plates are slipped in between the ties, the edge of the flange to be retained by the overhanging portion 20 or 28 being first engaged, and the opposite end of each plate inserted is, at the time of this first movement, downwardly inclined. The other edge of the flange is then at the upper part 90 of the adjacent beveled portion of element 14 or 24 as the case may be, and the plate is brought to horizontal position, the flange 95 sliding along the beveled portion. The distance between the lower part of the beveled portion and the wall 29, for instance, is equivalent to the width of the rail flange. The other plate is similarly inserted, and 100 both plates are moved to position above a tie, being bolted together and spiked down,

in an obvious manner. The securing devices for each rail are independent of those of the other rail of a track.

What is claimed is:

- 5 A rail securing device comprising a pair of plates adapted to support a rail independently of the other rail of a track, each plate including an upstanding member having an inner beveled edge for engaging a rail flange, and each plate carrying an upstanding member having an overhanging portion for engaging a rail flange, the overhanging portions of the respective plates being in reverse relation, all of said upstanding members being slotted, and bolts passing through the aforesaid slots. 20

In testimony whereof I affix my signature.

FRANK M. TUBBS.
